UNITED STATES PATENT OFFICE.

FREDERICK L. JOHNSON, OF WALLINGFORD, CONNECTICUT.

BICYCLE ALARM-WHISTLE.

SPECIFICATION forming part of Letters Patent No. 326,745, dated September 22, 1885.

Application filed September 29, 1884. (No model.)

To all whom it may concern:

Be it known that I, FREDERICK L. JOHNSON, of Wallingford, in the county of New Haven and State of Connecticut, have invented a new 5 Improvement in Bicycle Alarm-Whistles; and I do hereby declare the following, when taken in connection with accompanying drawings, and the letters of reference marked thereon, to be a full, clear, and exact description of the 10 same, which said drawings constitute part of this specification, and represent, in—

Figure 1, a side view; Fig. 2, a vertical central section; Fig. 3, a transverse section on line $x x$, looking upward.

15 This invention relates to a device constructed for attachment to bicycles, and by which an alarm or signal may be given by the rider to indicate his presence, the object of the invention being a simple construction of 20 whistle, which may be made as a fixture to the machine, convenient for the operator, and by which he may readily give a signal of his approach; and the invention consists in the construction of the signal, as hereinafter described, and more particularly recited in the 25 claims.

The whistle which I here represent is of the character known as "tubular" or "steam-whistles;" and it consists of a head, A, in the 30 outer end of which is a circular open slit, a . Below this head is the tube B, which in internal diameter corresponds substantially to the diameter of the slit a , the tube B being attached to the head by connections C, attached to the tube upon its outside, and below 35 its open end, the said connections extending to and united with the head above and outside the slit, and so as to bring the mouth of the tube into such relation to the open slit a that air passing through the slit will impinge 40 upon the edge of the tube and produce a sound, after the manner of what are known as "steam-whistles."

The head A is constructed with a seat, D, 45 upon which an elastic air-chamber, E, is set. This air-chamber is best made in the form of a hollow india-rubber ball, but when compressed to force the air it contains therefrom will resume its spherical condition and draw 50 in air to support it in that condition. The air-chamber E is fixed upon the seat D—say

as by an aperture through the ball—with a nut, F, upon the inside, into which a corresponding screw on the head enters, to clamp the edge of the hole in the ball between the 55 nut and the seat, and as seen in Fig. 2. The seat is provided with one or more shanks, G, to enter a corresponding socket or sockets, H. These sockets are constructed with a flange, I, by which the device may be attached to the machine, this attachment being intended to be made at the connection between the handle and the socket of the bicycle, and so as to stand centrally in front of the rider, in a convenient position for him to 60 press his hand upon the air chamber, as represented in Fig. 1, a portion of the bicycle-socket being there shown.

By compressing the air-chamber the air 65 therein is forced through the slit a and driven against the end of the tube B, so as to produce a loud whistle, the chamber instantly resuming its spherical shape when the hand is removed. Repeated signals may be given, or predetermined signals may be produced, 70 according to any code which may be established, as a long whistle, a short whistle, or one, two, or more whistles, in like manner as such signals are given by steam-whistles.

It will be understood that any of the known 75 constructions of whistles may be applied to be sounded by the compression of the air-chamber, and therefore, while I prefer the whistle I have described, I do not wish to be understood as limiting my invention thereto. 80

By the term "bicycle," as used in the specification and claims, I wish to be understood as including any of the numerous classes of vehicles which are arranged to be propelled by the rider.

I do not wish to be understood as claiming, broadly, a signal having an elastic air-chamber, by the compression of which air may be forced therefrom to sound the alarm, as such, I am aware, is not new.

I am also aware that such an elastic air-chamber has been attached to a bicycle, as a convenient means for signaling, such attachment therefore I do not wish to be understood as broadly claiming.

I claim—

1. The combination of the head A, construct-

ed with a circular slit at its lower end, and with a seat, D, also constructed for attachment to the bicycle, the tube B, having one end closed and the other open, the said tube attached to the head, with the open end adjacent to and concentric with the slit in the head, the attachment between the tube and the head being from points outside the tube and below its open end to corresponding points outside the head and above the slit, with an elastic air-chamber, E, opening into said head, substantially as described.

2. The combination of the seat D, a whistle attached thereto, said seat constructed with a shank, G, the elastic air-chamber E, attached to said seat and opening into the whistle, and socket H, constructed to receive said shank G, and fitted for attachment to a bicycle, substantially as described. 15

FREDERICK L. JOHNSON.
